(57) **CLAIM**

The ornamental design for a water cooled tankless loadbank, as shown and described.

DESCRIPTION

FIG. 1 is a front perspective view of a water cooled tankless loadbank showing my new design;

FIG. 2 is a rear perspective view thereof;

FIG. 3 is a right side elevation view thereof;

FIG. 4 is a front elevation view thereof;

FIG. 5 is a left side elevation view thereof;

FIG. 6 is a rear elevation view thereof;

FIG. 7 is a top plan view thereof;

FIG. 8 is a bottom plan view thereof; and,

FIG. 9 is a rear perspective view of an alternate embodiment thereof.

The broken lines shown represent unclaimed subject matter and form no part of the claimed design.
